UNITED STATES PATENT OFFICE.

MICHAEL J. HOEY, OF COLUMBUS, OHIO.

DRAFT-BEAM ATTACHMENT FOR RAILWAY-CARS.

SPECIFICATION forming part of Letters Patent No. 593,097, dated November 2, 1897.

Application filed May 3, 1897. Serial No. 635,440. (No model.)

To all whom it may concern:

Be it known that I, MICHAEL J. HOEY, a citizen of the United States, residing at Columbus, county of Franklin, and State of Ohio, have 5 invented certain new and useful Improvements in Draft-Beam Attachments for Railway-Cars, of which the following is a specification.

This invention relates to draft-beam attachments for railway-cars, and has for its object to avoid passing the draft-beam bolts through the draft-sills; to render the pulling strain of the draw-bars continuous from one end of the car to the other; to render the 15 draft-beams interchangeable, whereby they may be used right and left, and to improve, simplify, and render more strong and durable this class of draft devices generally.

To these ends my invention consists in the 20 features and in the combination, arrangement, and construction of parts hereinafter described, and set forth with particularity in the claims following the description, reference being had to the accompanying drawings, forming a part of this specification, wherein—

Figure 1 is a side elevation of my improved draft-beam applied to the draft-sills. Fig. 2 is a top plan view thereof. Fig. 3 is a detail 30 view of one of the stirrup-castings, and Fig. 4 is a detail view of one of the followers.

Referring to the drawings, the numeral 1 indicates the dead-block, 2 the end sill, and 3 the draft-sills, all constructed and arranged 35 as usual.

The draft-beam comprises two irons 4, each consisting of a central web 5 and lateral flanges 6. As one of these draft-irons is the exact duplicate of the other, the attachment 40 of one only need be described in detail, and for the sake of clearness either one or both of these draft-irons will hereinafter be referred to as the "draft-beam."

The forward end of the draft-beam is attached to the dead-block 1 by bolts 7, which also pass through the carry-irons 8, arranged on the under side of the draft and which supports the forward end of the draw-bar 9. Bolts 10 pass through the end sill 2 and 50 through the draft-beam. The rear ends of the draft-irons are provided with lateral lugs 11 and are attached to the draft-sills 3 by

bolts 12, which extend through said sills and through the draft-beam. Strap-bolts 13 pass through the lugs 11 and are bolted to the sides 55 of the subsills 14 by bolts 15.

The numeral 16 indicates the stirrup-castings, each consisting of a rectangular plate slotted at its opposite ends, as at 17, (see Fig. 3,) for the reception of the stirrup-bolts. Said 60 stirrup-casting is provided at its slotted ends with a square recess or cavity 18, in which the heads of the stirrup-bolts are adapted to seat, and is provided with longitudinal ribs 19 to afford strength and stiffness to the casting. 65 The stirrup-castings are countersunk into the draft-sills, as most clearly shown in Fig. 1, and are held in place by lugs extending each side of the draft-sills. Stirrup-bolts 20 are placed endwise in the slotted ends of the stirrup-castings, and their heads drop down into the recesses 18. The bolts pass down each side of the sills and extend through the draft-beam and through the follower guide-straps 21, arranged on the under side of the draft-beam. There is one such guide-strap for each 70 draft-iron, as most clearly shown in Fig. 2, and between the guide-straps and the top web of the draft-irons are arranged the followers 22. The adjacent faces of the followers are 75 provided with teats or bosses 23, over which are arranged coiled springs 24. A yoke 25 embraces the followers and is attached to the rear end of the draw-bar 9, as shown in Fig. 2, whereby the springs give a yielding strain 80 to the draw-bar both in pulling and backing. A safety-key 26 passes through the draw-bar and through coincident elongated slots 27, formed in the draft-beam, and operates to prevent the draw-bar from pulling out should 85 the draw-bar attachment break.

In order to prevent any endwise movement of the draft-beam, I form ribs 28 on the upper sides of the latter, which are mortised into the under side of the draft-sills, as shown. 90

By constructing and attaching the draft-beam in the manner described I avoid passing the draft-bolts through the draft-sills, a most serious objection, as the draft-bolts by the constant buffing and pulling strains wear 100 the bolt-holes in the draft-sills oblong and render the attachment useless in a short time. By attaching the draft-beam to the subsills by the strap-bolts, as shown, the pull-

ing strain of the draw-bars is rendered continuous from one end of the car to the other.

Another important advantage resulting from the improved construction described 5 resides in the fact that the draft-irons are interchangeable from either right or left, as by means of the webbed irons and the follower guide-straps both sides of the draft-irons are adapted for the support of the followers.

10 Having thus described my invention, what I claim is—

1. A draft-beam consisting of two parallel draft-irons, follower guide-straps arranged beneath the draft-irons, stirrup-castings projecting beyond the opposite sides of the draft-sills, stirrup-bolts extending through said stirrup-straps and through the draft-irons and follower guide-straps, in combination with followers arranged between the follower 15 guide-straps and the tops of the draft-irons, and coiled springs disposed between said followers, substantially as described.

2. A stirrup-casting for draft-beams, consisting of a rectangular plate having slots in 20 its opposite ends for the reception of bolts, and recesses or cavities formed in the upper sides of said slotted ends forming seats for the bolt-heads, substantially as described.

3. A draft-beam comprising two parallel 25 draft-irons each consisting of a central web 5, and upper and lower lateral flanges 6, follower guide-straps 21 arranged beneath the lower flanges 6 of the draft-irons, stirrup-castings projecting beyond the opposite sides 30 of the draft-sills, stirrup-bolts extending through said stirrup-straps and through the

draft-irons and follower guide-straps, followers 22 arranged between the said guide-straps and the upper webs 6 and provided with teats or bosses 23, and coiled springs 24 fitted at 40 their opposite ends over said teats or bosses, substantially as described.

4. The draft-beam consisting of two parallel draft-irons bolted to the draft-sills and having supported between them followers in- 45 closing coiled springs, laterally-extending lugs formed on the opposite sides of the rear ends of said draft-irons, bolts extending through the draft-irons and through the draft-sills, and strap-bolts extending through the 50 said lugs and bolted to the subsills of the car, the construction being such that the draft-irons can be interchanged one for the other, substantially as described.

5. A stirrup-casting for draft-beams, con- 55 sisting of a rectangular plate having slots in its opposite ends for the reception of bolts and recesses or cavities formed in the upper sides of said slotted ends forming seats for the bolt-heads, lugs formed on the under sides of 60 said plate for engaging the opposite sides of the sill, and longitudinal ribs formed on the upper and under sides of the plate, substan- tially as described.

In testimony whereof I have hereunto set 65 my hand in presence of two subscribing witnesses.

MICHAEL J. HOEY.
